(57) **CLAIM**

The ornamental design for an infant care apparatus, as shown and described.

DESCRIPTION

FIG. 1 is a front perspective view of an infant care apparatus in accordance with the present invention;

FIG. 2 is a front side view thereof;

FIG. 3 is a rear side view thereof;

FIG. 4 is a right side view thereof;

FIG. 5 is a left side view thereof;

FIG. 6 is a top plan view thereof; and,

FIG. 7 is a bottom plan view thereof.

The broken lines illustrating portions of the infant care apparatus form no part of the claimed design.
